HEAT TREATMENT OF MASSECUISTE IN
MIXER SPOUTS

Walter E. Smith, Honolulu, Territory of Hawaii

Application November 17, 1937, Serial No. 175,154

2 Claims. (Cl. 127—19)

This invention relates to the heat treatment of sugar bearing materials in the spouts of tanks containing such materials, such as the spouts of mixer tanks containing massecuite or magma.

5 More particularly, this invention is concerned with the provision of means for maintaining a predetermined temperature in mixer spouts and for control of such temperature in relation to the temperature of the massecuite within the tank.

10 In recent years much attention has been given to the purging of low grades of sugar and the separation of the sugar crystals from the molasses in which they are suspended. After evaporation of the massecuite to ensure the crystallization of the greatest amount of sugar the massecuite has a low temperature and is very viscous.

15 Reheating of the massecuite within the mixer increases the fluidity to such an extent that the massecuite may be effectively purged in the centrifugals. Although the time of purging has been reduced and the quality of sugar produced has been improved by reheating the massecuite in the mixer, still there has remained an undesirable condition in the centrifuging. Unpredictably, the centrifugals would vibrate or oscillate in a dangerous fashion creating a terrific disturbance, often damaging the machine so that it had to be replaced or shut down for repairs. The unbalanced condition of the centrifugal seemed

20 to occur, at times, in spite of the fact that the operator in charge of the centrifugal was experienced and possessed a high degree of skill gained by his having loaded it many times. The situation gave rise to the use of the expressions "good sugar" or "bad sugar" by the centrifugal operators, the "bad sugar" being that which caused the worst unbalanced condition and its most frequent occurrence.

25 Many efforts to overcome the unbalancing have been made. These have universally been in the nature of improvements to the centrifugal or its associated machinery. But neither the centrifugal operators nor the engineers and inventors in the art realized wherein the fault lay. Hence they failed to solve the problem of unbalanced centrifugal operation.

30 Though many had noticed the retarded nature of the initial flow from the delivery spouts of the mixer when the gates were opened to charge the centrifugal, it was generally thought that this was due to a settling of the sugar grains or to the absence of a velocity head at the moment of gate-opening. This condition was thought to be

35 unavoidable. No one realized that in this phe-

nomenon might be found the answer to the unbalancing of the centrifugal.

My invention lies in the discovery that unbalanced centrifugal operation is not usually due to the machine itself but to the unequal viscosity 5 and hence unequal purging of all portions of the material loaded into the centrifugal basket.

I have discovered that the condition of the massecuite within the mixer spouts is not due to the concentration of the sugar grains but is due 10 to the fact that the relatively large heat radiating surface of the spouts has caused chilling of the massecuite in the spout and consequent increase in viscosity.

I have discovered, also, that this portion of 15 massecuite with increased viscosity, even when the centrifugal is in charge of an experienced operator, is liable to cause unbalancing and dangerous oscillation of the centrifugal particularly if the massecuite contains high percentages of 20 impurities of the type which are very viscous except at high temperatures. I have discovered that the massecuite in the mixer spout must be maintained at the same temperature as the main body of massecuite in the mixer if balanced 25 centrifugal action is to be achieved. I have discovered that the provision of heating means broadly to raise the temperature of the massecuite in the mixer spout is insufficient to ensure balanced 30 centrifugal operation since the raising of the temperature of the body of massecuite in the spout higher than that of the body in the mixer tank will result in unequal purging.

Therefore it is an object of this invention to attain balanced centrifugal operation by ascertaining and correcting the cause of unbalanced 35 operation.

Another object of my invention is to provide means for maintaining the temperature of the material in the mixer spout at the same temperature 40 as that in the mixer itself.

Another object of my invention is to provide automatic means for regulating the temperature of the massecuite in the mixer spout and maintaining it at approximately the same temperature 45 as the massecuite in the body of the mixer.

Other objects and advantages of my invention will become apparent as it is described in connection with the accompanying drawing.

In the drawing the single figure shows diagrammatically a mixer spout with a jacket for the circulation of heating water and means for maintaining it at the desired temperature according to the principles of my invention.

Referring to the drawing the mixer tank 10 55

contains the massecuite received from the crystallizers and held for delivery to the centrifugal 12. The mixer may contain means for reheating the massecuite, such as a rotating coil containing hot water circulating therethrough for reheating the massecuite to any desired temperature. Inasmuch as these coils form no part of my invention, illustration of them has been omitted in the drawing.

10 The mixer tank converges toward its bottom and has secured thereto a spout designated generally by the numeral 14. The spout is provided with a gate 80 which is vertically slidable by means of pivoted links 82 connected therewith 15 and operated by a hand lever 86 in a well known fashion. Heretofore when the machine operator opened the gate and found the viscous portion of the massecuite in the spout to be slow in coming out he would move the gate up and down, chopping off portions of the massecuite as it bulged out, thus trying to distribute the viscous lump in small parts in the centrifugal. This procedure, however, was not satisfactory for the reason that very often the cool lump or lumps of viscous 25 massecuite would remain in the centrifugal basket while the hot massecuite was purging and these lumps would be very slow to purge, causing the aforementioned unbalancing and oscillation of the centrifugal. This is one of the disadvantages 30 that my present invention is designed to overcome.

The mixer spout 14 may consist of a hollow casting of one or more parts which is provided with a chamber or passage 16 entirely around 35 and within its walls for the circulation therein of hot water in order that the spout and material therein may be maintained at a desired temperature. The spout, in cross-section, is generally rectangular with rounded corners to facilitate casting. Opposite sides of the outside walls of the spout have large circular openings 20 over which are secured circular plates or covers, such as 18. The covers may be removed for the purpose of cleaning out the water jacket, as occasion 40 requires. In each cover there is provided an opening into which is screwed a pipe joint, such as 22, to which may be connected pipes such as 24 and 26. The pipe 24 may be connected with the discharge of the pump 28 while the pipe 26 comprises the return to a reservoir or tank 30 containing 45 hot water. This tank is connected with the intake of the pump 28 by a pipe 32. The water in the tank is heated by a steam coil 34, the steam being supplied to the coil through a pipe 36 50 containing a solenoid operated valve 38. A steam supply may be connected to the entrance chamber 40 of the valve by a pipe 42. An electrical solenoid 44 is mounted on top of the valve casing. The armature 46 of this solenoid is connected 55 with the stem 48 of the valve and the stem 48 has on its lower end a valve head 50 adapted to fit upon a seat 52 provided therefor in the valve casing. A coil spring 54, acting on the armature 46, holds the valve normally open.

60 For controlling the operation of the valve and its solenoid I have provided a thermostatic device including a gas-filled metal bulb 60 inserted in a wall of the mixer. This thermostatic device causes an electrical contact 62 to rise as the 65 temperature of the massecuite rises and the gas within the bulb expands. The details of the mechanism for causing movement of the contact in response to the increase in temperature need not be described in detail inasmuch as such 70 thermostatic devices are in common use for re-

mote temperature readings or thermostatic controls. The contact 62 is connected by a wire 64 to one pole of a source of power (not shown). Also for controlling the solenoid 44 I have provided a thermostatic device including a gas-filled metal bulb 70 inserted in the wall of the hot water tank 30. This thermostatic device operates and is constructed similar to the thermostatic device 60 and is connected for operation of a movable electrical contact 72. This contact rises as the temperature 10 increases in the hot water tank 30. The contact is connected by a wire 74 to one end of the solenoid 44, the other end of the solenoid being connected by a wire 76 to the other pole of the source of power. 15

In operation, when the massecuite in the tank 10 becomes heated to a predetermined temperature the thermostatic device 60 will cause the contact 62 to rise and separate from the contact 72 as shown. This will break the circuit and deenergize the solenoid 44 which then will allow the valve to open by operation of the spring 54. Steam will thus be admitted to the coil 34 causing heating of the water in the tank 30. As the hot water is caused to circulate by the pump 28 25 through the pipes 32 and 24 and through the jacket or passage 16 around the mixer spout, the massecuite in the mixer spout will become heated. Preferably the water will be circulated in large volume through the jacket 16 at a temperature 30 approximately equal to the temperature at which it is desired to maintain the massecuite in the spout. Therefore the thermostatic device 70 in the water tank will be set at a temperature slightly above the desired temperature of the massecuite 35 in the spout to provide for heat radiation as the heating water circulates through the system. When the water in the hot water tank 30 has reached the desired temperature the thermostatic device 70 will cause the contact 72 to rise 40 and engage with the contact 62 completing the circuit through the solenoid and causing the head 50 of the valve to press upon its seat 52, shutting off the supply of steam.

If the temperature of the massecuite in the 45 mixer drops the contacts 62 and 72 will be maintained in engagement for a slightly longer period and until the water in the tank 30 has dropped sufficiently to cause the contact 72 to disengage the contact 62; and the steam supply will be shut 50 off when the contact 72 re-engages the contact 62 in the lowered position of the contact 62. If the temperature of the massecuite in the mixer tank rises the contact 62 will rise and the contact 72 will have to rise farther before engaging it, thus 55 allowing the steam to heat the water to a higher temperature before the valve closes. Thus it is apparent that the means I have provided will maintain the temperature of the massecuite in the mixer spout at approximately the same temperature as the massecuite in the tank. 60

Obviously many methods and types of apparatus for maintaining the temperatures of the massecuite in the spout and in the tank approximately equal will occur to those skilled in the 65 art. Therefore I do not limit the invention to the specific embodiment shown.

I claim—

1. Apparatus for improving the operation of centrifugal machines when purging sugar-bearing materials that have been heated above atmospheric temperature in a tank to increase their fluidity, said apparatus including a tank adapted to contain said heated sugar-bearing materials, a spout extending a substantial distance from the 70 75

5 tank for delivering said material to a centrifugal, said spout having a chamber around it, and means for circulating heated fluid through said chamber at a temperature to keep the material in the spout at substantially the same temperature as the material in the tank.

10 2. Apparatus for improving the operation of centrifugal machines when purging sugar-bearing materials that have been heated above atmospheric temperature in a tank to increase their

fluidity, said apparatus including a tank adapted to contain said heated sugar-bearing materials, a spout extending a substantial distance from the tank, and heating means associated with said spout for maintaining the temperature of the material within said spout at a temperature substantially equal to that of the material in the tank.
